CLAIM

The ornamental design for a laboratory glassware, as shown and described.

DESCRIPTION

FIG. 1 is a front perspective view of a laboratory glassware, showing my new design.

FIG. 2 is a side view of the laboratory glassware of FIG. 1. FIG. 3 is a top plan view of the laboratory glassware of FIG. 1; and,

FIG. 4 is a bottom plan view of the laboratory glassware of FIG. 1.

Any broken line portions of FIGS. 1–4 are included to show unclaimed subject matter only and form no part of the claimed design.

1 Claim, 4 Drawing Sheets(56)
